HEEL PROTECTOR

Sarah Craven Maloy, Knoxville, Tenn.

Application May 3, 1948, Serial No. 24,762

8 Claims. (Cl. 36—1)

1

This invention relates to improvements in heel protectors and is designed for the purpose of being worn in combination with backless, and strap heel or sling strap shoes and sandals.

In a sling strap pump or strap heel or open back shoe, the heels of the wearer, except for stocking covering, are open and exposed to inclement weather, such as rain, snow and cold temperatures, as well as water and mud splashed from streets, roads and walks.

Accordingly, it is one object of this invention to provide an efficient heel protector to be used in combination with such footwear which will, when in use, protect the wearer's heels from inclement weather, such as rain and snow, as well as from the discomfort of cold temperatures.

A further object of this invention is to provide a heel protector to be used in combination with such footwear so designed as practically to convert such open heel shoes, when used in combination with them, into conventional high counter pumps or low quarter shoes.

A further object of this invention is to provide such a heel protector for footwear that it may be readily attached to and detached from the shoe at the will of the user, so as quickly to convert such shoes from open-heel footwear to practically closed-heel footwear, and the reverse.

Said heel protector may be made with conventional stiff counter or of thin, pliable material, which may be carried easily in a pocket or lady's handbag, to be used when the occasion may dictate.

One embodiment of this invention is illustrated in the accompanying drawings, in which,

Fig. 1 is a perspective view of the protector embodying this invention;

Fig. 2 is a side elevation of this protector shown attached to a sling strap pump; and

Fig. 3 is a perspective view of the protector removed and showing the retaining strap in an open position.

Referring now to the drawings, the numeral 5 designates the heel protector generally, which preferably is made from any soft flexible material and may be either leather, leatherette or plastic, or any other substantial material. The protector may be made in several pieces and sewn together or may be molded in one piece to fit the heel of the wearer.

The protector is provided with an insole or bottom section 6, which is shaped to conform to the bottom of the heel of the wearer's foot, or to the sole of the shoe at the heel portion thereof.

Attached to the bottom section 6 is an upstanding partially surrounding side 7, forming a high counter or upper of the heel portion of the protector. This side or counter 7 preferably extends upwardly above the upper edge of the shoe strap 17, inwardly of the latter, forming a closed heel portion for the shoe.

This upstanding side 7, when the protector is not formed in one integral piece, may be attached to the bottom 6 along a line 8, by means of stitching, glue, or other fastening. On the inside of both the bottom 6 and the side 7, may be sewn or glued a fabric lining 9, if desired, to give added comfort to the wearer of the protector. The fabric lining 9 is stitched to the side 7 by stitches 10 and to the base 6 along the line 8.

Provision is made for attaching the protector 5 to the shoe, preferably to the strap 17. While any suitable fastening means may be used for the purpose, I have shown a loop or strap 11 for detachably fastening the protector thereto. In this form, the strap or loop 11 is securely attached to the upstanding side member 7 at the top of the back thereof, although similar loops or fastenings may be used at other points, if desired. The strap 11, as shown in Figs. 1 and 3, may be stitched or sewn at one end 15 thereof to the side member 7, or if the protector is made of a plastic material, the strap 11 may be made integral instead of stitched. However, the heel protector may be attached to the shoe strap and upper part of the shoe with any number of straps or detachable fastenings to give it greater stability in use, or may be attached to the shoe by snap fastenings located in the inner sole and fastening into counter-sunk members in the permanent sole of the shoe, or by other suitable detachable fastenings, especially when the protector is sold as a detachable part of the shoe, an accessory thereon capable of removal.

Carried upon the end of the strap 11, opposite the end attached to the side 7, is the head or top portion of a snap fastener 12, and attached to the upstanding member 7 is the opposite or companion part 13 of the snap fastener. As shown in the drawings, the snap fastener may be of any conventional type, or if desired, other suitable form of detachable fasteners may be substituted therefor, such as a buckle, which could be used quite satisfactorily. Further, it would not be necessary to provide a detachable fastening for the strap 11, but the end 14 of the strap 11 could be sewn or otherwise attached as at 15 to form a closed loop.

The use of this protector is best illustrated in

Fig. 2 wherein is shown a lady's sling strap pump 16, and is one form of footwear to which it may be applied, and which has a heel strap 17 adapted for surrounding the wearer's heel. Occasionally these straps are provided with some adjustable means such as a buckle 18, although frequently they are made in one piece. As is well known, the heel of the wearer in this type of shoe or pump is open and exposed adjacent the strap 17.

When the weather is inclement and the wearer desires to protect her heel, the protector 5 is placed upon the heel portion of the sole. The strap 17 then will surround the top portion of the protector 5 as shown. The strap 11 then is looped down over the strap 17 and snapped into place by means of the fastener 12. This combination holds the protector on the wearer's heel as long as it is desired to be worn. It may be removed simply and easily even without removing the shoe, by detaching the snap fastener 12-13 and separating the strap 11 from the strap 17, when the protector may be withdrawn entirely from the shoe and heel.

It is to be understood that changes in material, fastenings, type of loop, strap and stitching may be made without departing from the spirit of this invention, except as defined in the claims.

I claim:

1. A heel protector adapted for use in combination with a strap heel shoe or open heel shoe, comprising an upstanding member for detachable application to such shoe and of sufficient height to extend above the lower margin of the strap and forward to close the cut away portion of the shoe with which it is worn, fully covering that portion of the back and sides of the wearer's heel and foot which would otherwise be exposed by the cut away portion of the shoe between the strap and the sole with which it is worn, a strap affixed at one end to the top side of the upstanding member in position to embrace said shoe strap, and a separable fastener affixed to the opposite end of said protector strap and to the back of said upstanding member to secure the strap in a loop for receiving the strap of said shoe.

2. A heel protector comprising an upstanding side member shaped fully to cover the back and sides of the wearer's heel, and a retaining strap affixed to the side member and having detachable means connected therewith for detachable connection with a strap of a backless shoe to detachably attach the heel protector to the shoe.

3. A heel protector adapted to be worn with an open back strap shoe comprising a bottom member formed to fit the shape of the bottom of the wearer's heel, and an upstanding member attached to the bottom member to form a protective covering for the heel of the wearer, said upstanding member being high enough to reach at least above the bottom of the strap of the shoe with which it is worn and extending forward about the sides so as to fill completely the cut away portion of the shoe with which it is worn between the shoe strap and the permanent sole, and a retaining strap in the form of a loop at-

tached to the back of said upstanding member adapted to detachably receive therethrough a strap of the shoe with which it is worn.

4. A heel protector adapted to be worn in combination with an open back strap shoe comprising a stocking protective member, having a bottom formed to fit the shape of the bottom of the wearer's heel and an upstanding member affixed to the bottom member to form a covering for the back and sides of the wearer's heel, and a strap affixed to a portion of the upstanding member in position to embrace and receive the strap of the shoe with which it is being worn, and a separable snap fastener carried by the opposite end of the protector member strap and the upstanding member to secure said strap in a loop for receiving the strap of said shoe.

5. A heel protector comprising an upstanding side member shaped to partially cover the back and sides of the wearer's heel, and a retaining strap affixed to the side member and having means substantially at the upper portion of said member constructed to detachably receive a strap of a backless shoe.

6. A heel protector adapted to be worn with an open heel shoe having a strap about the back thereof, comprising a stocking protective member formed to fit the heel of the wearer, and a loop affixed to the member and mounted substantially at the upper portion thereof adapted to embrace the strap of the shoe to hold the protective member in place.

7. A heel protector comprising a bottom member formed to fit the shape of the bottom of the wearer's heel, an upstanding member attached to the bottom member to form a protective covering for the heel of the wearer, and a retaining strap in the form of a loop attached to the upper portion of the back of said upstanding member adapted to receive therethrough a strap of a shoe.

8. A heel protector adapted to be worn with a strap back shoe, comprising a stocking protective member having a bottom formed to fit the shape of the bottom of the wearer's heel and an upstanding member affixed to the bottom member to form a covering for the back and sides of the wearer's heel, a strap affixed at one end to the top of the upstanding member in position to embrace the shoe strap and a separable snap fastener carried by the opposite end of the protector member strap and the upstanding member to secure said strap in a loop for receiving the strap of said shoe.
